UNITED STATES PATENT OFFICE.

GEORGE S. CROSBY, OF BRIDGEPORT, CONNECTICUT.

TOY.

SPECIFICATION forming part of Letters Patent No. 276,524, dated April 24, 1883.

Application filed August 11, 1882. (No model.)

To all whom it may concern:

Be it known that I, GEORGE S. CROSBY, a citizen of the United States of America, residing at Bridgeport, in the county of Fairfield and State of Connecticut, have invented certain new and useful Improvements in Toys, of which the following is a specification, reference being had therein to the accompanying drawing.

10 My invention relates to mechanical toys, and has for its object to provide a toy to which a rotary and rocking motion is imparted; and with these ends in view my invention consists in the details of construction and combination 15 of elements hereinafter fully described, and then specifically designated by the claim.

In order that those skilled may more fully understand the construction and operation of my improved device, I will proceed to describe 20 the same in detail, referring by letter to the accompanying drawing, forming part of this specification, in which the figure is a view in elevation of my improvement.

A is the body of the device, to which is attached a rod, B, and suspensory hook C. D 25 are detachable and adjustable balance-arms, provided with weights E E.

The *modus operandi* of my improvement is

as follows: I attach the rod B and weighted arms D D to the body A, and affix to the free 30 end of said rod any suitable toy, F. I then mount the hook C upon a standard, G, adapted for the same, and by the adjustment of the arms D throw the center of gravity through the point of suspension. When the toy F is 35 revolved it will acquire a rocking motion, as will be readily understood.

I have illustrated my invention by a toy ship counterbalanced by small toy boats, since the rocking motion is especially applicable to 40 toys of this description; but I am enabled to use different kinds of toys without departing from the spirit of my invention.

What I claim as new, and desire to secure by Letters Patent, is—

The body A, provided with hook C, adjustable balance-arms D, having toy weights E, and rod B, with toy ship F affixed thereto, in combination with the standard G, substantially as and for the purpose set forth.

In testimony whereof I affix my signature in presence of two witnesses.

GEORGE S. CROSBY.

Witnesses:

W. T. HAVILAND,
JOSEPH A. JOYCE.
